WITNESS: *John Donovan*

UNITED STATES PATENT OFFICE.

HOWARD A. TAYLOR, OF WATERTOWN, NEW YORK.

LIQUID RHEOSTAT.

Application filed July 8, 1924. Serial No. 724,836.

To all whom it may concern:

Be it known that I, HOWARD A. TAYLOR, a citizen of the United States, residing at Watertown, in the county of Jefferson and

5 State of New York, have invented new and useful Improvements in Liquid Rheostats, of which the following is a specification.

This invention relates to electrical apparatus, particularly rheostats, and has for its 10 object the provision of a novel device of this character using a liquid as the resistance element, the construction and arrangement being such that connections may be made to obtain any desired resistance for 15 controlling a circuit.

An additional object is the provision of a device of this character which will be simple and inexpensive in manufacture, easy to install, positive in action and a general improvement in the art.

With the above and other objects and advantages in view, the invention consists in the details of construction and arrangement of parts to be hereinafter more fully described and claimed and illustrated in the 25 accompanying drawings, in which:

Figure 1 is a perspective view of the device.

Figure 2 is a vertical section on the line 30 2-2 of Figure 1.

Figure 3 is a detail view of one of the terminal members.

Referring more particularly to the drawing, the numeral 10 designates the body of 35 the device which in actual practice may be formed as a rectangular or other shaped block of cement or other suitable insulating material cored or drilled to provide spaced recesses or pockets 11 for containing a suitable liquid 12 having any desired conductivity or resistance to the passage of an electrical current.

Extending transversely through the block 10 in spaced parallel relation and traversing 45 the pockets 10 are bolts 13, preferably of brass, surrounded by steel sleeves 14 provided for the purpose of preventing or retarding corrosion. The heads 15 of the bolts engage against one side of the body, and on 50 the other ends of the bolts are clamping

nuts 16 which engage the opposite side of the body.

It will be noted that there are three pockets 11 and three sets of bolts. Connection may be made to any of the bolts and the 55 bolts of the different series may be connected by bridging elements 17. In this way it is apparent that the liquid path for the current may be made as short or long as desired so as to vary the resistance to meet the requirements of the circuits in which the device is used.

While I have shown and described the preferred form of the invention it is to be understood that I reserve the right to make 65 such changes in the construction as will not depart from the spirit of the invention or the scope of the subjoined claims.

Having thus described my invention, I claim:—

1. A rheostat comprising a body of insulating material formed with a plurality of pockets containing a more or less current conducting liquid, and a plurality of terminals extending to each pocket at spaced 70 points, each terminal including a bolt extending transversely through the body in intersecting relation to the pockets.

2. A rheostat comprising a body of insulating material formed with a plurality of 75 pockets containing a more or less current conducting liquid, and a plurality of terminals extending to each pocket at spaced points, each terminal including a bolt extending transversely through the body in intersecting relation to the pockets, and a non-corrodible metallic sleeve surrounding each bolt.

3. A rheostat comprising a block of non-conducting cement formed with a plurality 80 of pockets containing liquid, a series of bolts extending through the body and traversing the respective pockets, clamping nuts on the bolts, and elements engageable with the bolts in the successive series for making 85 changes in the length of the liquid path to be travelled by the current.

In testimony whereof I affix my signature.

HOWARD A. TAYLOR.
